UNITED STATES PATENT OFFICE

MARY C. WINE, OF NEW YORK, N. Y.

ADJUSTABLE READING SUPPORT FOR CHAIRS

Application filed May 21, 1931. Serial No. 538,998.

This invention relates to attachments for articles of furniture, such as seating devices, and has particular reference to collapsible book supports for chairs.

- 5 The seating device herein chosen for illustration is one of the arm chair type, only as much of the same being shown as is sufficient for a complete understanding of the invention; and one of the objects involved is the 10 provision of an organization in which the constituent elements are so coordinated structurally and functionally as to be readily attachable to and removable from the arms of a chair.
- 15 As the new support obviates the necessity of using a table or other adjacent support, such as has heretofore been utilized, and as it is desirable to render the said support suitable for use with different sizes of chairs, and also 20 for different purposes with the same chair, another important object of the invention is to provide a support which is adjustable transversely, as well as in fore and aft directions.
- 25 During adjustment in these latter directions part of the structure is movable between an inclined position, as for supporting a book or article for reading or writing purposes; and a horizontal position, as when the said 30 structure is used as a table, this being a further object of the invention.

Since the support is movable with a chair, subsequent to attachment and as it is desirable to provide for free and unrestricted movement of an occupant of a chair, without danger of accidentally moving the support, a still further object is the provision of locking means for securing the parts of the structure in any of the aforesaid adjusted positions.

40 The transversely adjustable or horizontally disposed position includes a base, which is reinforced by a unitary structure, to render the same strong and light. Means carried by the fore and aft or vertically movable portion 45 cooperate with the reinforcement. This last mentioned portion is further supported on the first portion, this being by a novel strut; and yet another object of the invention is to utilize the said strut both for supporting and locking purposes.

With the above indicated objects in view the invention resides in a certain novel construction which, including combinations and arrangements of parts, is herein clearly described, and fully illustrated in the accompanying drawing, in which:

Fig. 1 is a front elevational view.
 Fig. 2 is a diagrammatic end view.
 Fig. 3 is a fragmentary bottom plan view.
 Fig. 4 is a fragmentary detail view.
 Fig. 5 is an enlarged vertical section taken on the line 5—5 of Figure 1; and
 Fig. 6 is a partial plan view taken on the line 6—6 of Fig. 5.

Similar numerals refer to corresponding parts throughout the several views.

Telescopically movable in tubular marginal or edge portions 10, 11 of a base section 12 are coacting tubular portions 13, 14 of a base section 15. The section 12 has metallically attached thereto a resilient clip 16; and the section 15 a like clip 17, so that on disposing the base in contracted condition between the arms 18, 19 of a chair and then extending the said sections the spring clips are effective to resiliently grip the chair arms at any convenient place, such as in rear of arm supports 20, 21. Terminals 22, 23 of the respective clips act as stops for arresting outward movement of the base sections, while the latter have thereon cushioning or felt strips 24, 25 to protect the arms of the chair.

The device includes a relatively movable leaf or book supporting portion 26. Attached to an angularly disposed flange 27 of the leaf are curled tongues or hinge members 28, 29, which loosely embrace the hollow rib 10. A keeper 30 for retaining in open condition the leaves of a book, when the latter is disposed on the leaf 26; or for holding any other material on the said leaf, is attached to the flange 27, and this keeper may also have thereon a hinge member 31 for embracing the rib 10. The leaf 26 is therefore hingedly movable between a folded or flat position as seen in Fig. 5, for instance, and an inclined position; and since it is not necessary to move the leaf to a vertical position its movement may be arrested by stops, as at 32, formed by the hinge members.

Struck out of the material 26 are ears 33, 34, which form barrels or hinge portions. A foldable strut or support 35 for the leaf is provided with curled ears 36, 37; and as these latter are loosely embraced by the said ears 33, 34, the strut and its leaf are collapsible, as seen in the said Fig. 5. The strut is provided with extensions 38, 39, and as the sections 12 and 15 have therein mating apertures 40, 41, said terminals find an anchorage in these apertures and thereby lock the structure in the set-up position.

My collapsible book support is suitable for use with any appropriate chair; such as in the home, club, hospital, or library; or with seating devices of vehicles or the like. Constructed of any light metal or material, the support may be painted or treated to harmonize with any color scheme. The device is very compact, and is well suited for quantity production.

As the hereinbefore described construction admits of considerable modification, without departing from the invention, the particular arrangements shown should be taken as illustrative, and not in a limiting sense. Therefore, the scope of the protection contemplated is to be taken solely from the appended claims, interpreted as broadly as is consistent with the prior art.

I claim as my invention:

1. An attachment for a chair comprising a base having adjustable sections, an inclined book support movably carried on said sections, means for holding said support in the inclined position, and means including said first means for holding said sections adjusted.

2. An attachment for an arm chair comprising a base having adjustable sections, terminal means carried by said sections for attaching the latter to the arms of a chair, an inclined book support movably carried on said sections, means for holding said support in the inclined position, and means including said first means for holding said sections adjusted.

3. An adjustable book support for an arm chair comprising base sections having therein registering apertures, an inclined adjustable leaf movably carried at one of its edges on said base, means disposed between said base and the opposite edge of said leaf for supporting the latter in the inclined position, and an extension carried on said means and disposed in the registering apertures of said sections for holding said sections adjusted.

4. An attachment for an arm chair comprising a base having adjustable sections, telescopically coacting tubular marginal portions integral with said sections, an adjustable supporting leaf for a book, and hinge means carried by said leaf and loosely embracing one of said portions, whereby said leaf is movable between horizontal and inclined positions.

5. An adjustable book support for an arm chair comprising a base having relatively movable sections, telescopically coacting tubular marginal portions integral with said sections, a movable leaf, hinge means carried by one edge of said leaf and loosely embracing one of said portions, and a support disposed between said base and the opposite edge of leaf for holding the latter in an inclined position.

6. An adjustable book support for an arm chair comprising base sections having therein registering apertures, an inclined adjustable leaf movably carried at one of its edges on said base, means disposed between said base and the opposite edge of said leaf for supporting the latter in the inclined position, extensions carried on said means and disposed in the registering apertures of said sections for holding said sections in an adjusted position.

7. An adjustable book support for an arm chair comprising in combination a base having relatively movable chair sections for resting on the arms of a chair telescopically coacting marginal portions integral with said sections, which latter are provided with registering apertures, a movable leaf, hinge means carried by one edge of said leaf and loosely embracing one of said portions, a support disposed between said base and the opposite edge of said leaf for holding the latter in an inclined position, and extensions carried by said support and disposed in said registering apertures for holding said sections adjusted.

8. The combination with a chair having a pair of arms, of a book support including outwardly extensible base sections, means for releasably associating the outer terminals of said arms with said sections, a movable leaf, means loosely connecting one edge of said leaf to one edge of said sections whereby the opposite edge of said leaf is swingable between inclined and horizontal positions, and means for supporting said leaf in the inclined position, said latter means adapted also to hold said sections extended.

9. A foldable book support for an arm chair comprising telescopically engaging movable base sections having thereon opposed terminals for engaging the arms of a chair, a movable leaf, a first hinge means on said leaf for attaching the front edge of said leaf to one of the edges of said base, a second hinge means carried near the rear edge portion of said leaf, and a leaf support movably cooperating with said leaf whereby said leaf is movable between inclined and flat folded positions.

10. A foldable book support comprising telescopically engaging base sections having front and rear edges, a book supporting leaf hinged secured to the front edge of one of said base sections whereby said leaf is mov-

able between upright and horizontal positions, and means resting on said base sections and hingedly secured to said supporting leaf whereby to hold said supporting leaf in the desired book reading position.

5 Signed at New York in the county of New York and State of New York this 19 day of May A.D. 1931.
